AUTOMATIC OBTURATOR WITH VARIABLE
OPENING FOR CINE-PICTURE TAKING
APPARATUS

Jean Weissbrodt, Boulogne-sur-Seine, France

Application May 22, 1935, Serial No. 22,856
In France May 23, 1934

9 Claims. (Cl. 88—19.3)

The present invention concerns an obturating device with variable opening for cine-picture taking apparatus and the like, especially of the type comprising two rotary obturators with two or more wings and mounted behind each other on the same shaft, the variations of the opening being secured by the lag of one of these obturators with respect to the other.

The variation of opening of the obturating device permits not only of a variation of the time of exposition but also of the realization of tricks known in the cinematographic technic under the names "found" and "found enchaîné" and consisting in taking first a series of pictures with progressively decreasing exposition and then, in the case of "found enchaîné" in impressing, on the same portion of the film, a series of pictures with increasing exposition, or inversely.

In the known devices of the specified type, the variation of the opening is generally effected by hand with aid of a mechanism built for example in the following manner:

Two obturators 1 and 2 (Fig. 1) for example with two wings, are mounted on a shaft 3 in front of a film F.

They are attached to hubs 4 and 5 (Figs. 2 and 3) fitted with friction on the shaft 3, sliding in its longitudinal direction and carrying a grooved bushing 6. This shaft is provided with a finger 7 passing through a longitudinal slit in the hub 5 and a helicoidal slit in the hub 4. The hub 5 and consequently the obturator 2 are attached to a pinion 8 driven by the mechanism of the apparatus.

The variation of opening is controlled by a system of—not represented—cranks acting upon the bushing 6 and imparting a shifting movement to the shaft 3, the finger 7 imparting a rotary movement to the obturator 1 owing to the helicoidal slit of the hub 4 connected to this obturator. The system of cranks is controlled by hand by means of a button, this control being possible either during the standstill of the apparatus or during its run; owing to friction the shaft 3 is driven by the pinion 8 and takes along the obturator 1 owing to the finger 7.

Now the devices of this kind present a great drawback especially for the realization of the proceedings known as "found" and "found enchaîné". It is known, indeed, that this proceeding requires a continuous and uniform variation of the opening of the obturator during the passage of the corresponding length of the film in front of the objective.

Now it is obvious that when the control of the

variation of opening of the obturator is effected by hand, as described above, this variation can never, at one part, be perfectly continuous and uniform, and, at the other part, the control of the speed of variation with regard to the chosen length of the film will be difficult and uncertain.

The present invention has the purpose to obviate this drawback.

The invention is characterized by the fact that the variable opening of the obturator is controlled automatically by the driving elements of the apparatus through the medium of a mechanism devised in a manner to render this variation of opening continuous and uniform.

This mechanism comprises an engaging gear 15 operated by hand so as to be engaged at will by the operator, an audible alarm announcing the complete closing or opening of the obturator.

This mechanism can equally comprise a speed changing gear permitting of the variation of duration of closing or opening of the obturator and consequently of the number of pictures taken for the "found" proceeding.

Two forms of construction of this mechanism applied to an obturator of the type above specified will be described hereafter merely in the way of examples and with reference to the drawings appended. In these drawings represent:

Fig. 1 a diagrammatic view of the obturator with variable opening, as above referred to;

Fig. 2 a view in elevation of this mechanism and of the obturator, looking at the side of the case, not shown;

Fig. 3 is a plan view of this mechanism;

Figs. 4, 5 and 6 are elevational views of parts of the engaging gear device in positions of disengagement and engagement;

Fig. 7 shows in the same elevational view another embodiment of this device, and

Fig. 8 is an axial section through a detail of the audible alarm device;

Fig. 9, finally, is an axial section through a part of the speed changing gear.

Fig. 2 shows a toothed crown 9 of the motor drum, meshing with a pinion 10 fixed on a shaft 11 journalled freely in the case 12 and in a plate 13 of the apparatus. This shaft 11 carries equally a horse head 14 disposed with slight friction with aid of a spring 15, and several pinions 16, 16' and 16'' (Fig. 3).

The horse head 14 carries an equal number of pinions 17, 17' and 17'' fixed to each other and loose on an axle. They mesh with the pinions 16, 16' and 16'' respectively.

On an axle 18 lodged in the plate 13 and pro-

vided outwardly with a knurled button 19 is fixed a pinion 20 (Fig. 2) which can mesh with the pinion 17 and is attached to an eccentric 21 provided with a slot for example in the shape of a spiral of Archimedes, as indicated at 22 in Fig. 4.

5 The free extremity of the horse head 14 is supported by a projection 23 of the upper arm of a cranked lever 24 articulated to the frame of the apparatus and pulled upwardly by a spring 25.

10 The shaft 26 carries a crank 27 fixed to the same and is attached to the system controlling the opening of the obturator, viz. to the crank 28 acting upon the grooved bushing 6.

15 A rod 31 articulated at 29 to the crank 27 is set into a to and fro movement by the eccentric 21 through the medium of a pin 32 fixed to this rod 31 and displacing itself along the slot 22. This rod is guided by the axle 18 engaging a slot 33 provided in this rod.

20 An outer button 34 maintained by a spring 35 applies against the upper arm of the lever 24 and serves for lowering this lever against the action of a spring 25.

25 On the shaft 26 is loosely mounted a cam 30 comprising two beaks, the one 36 whereof applies against the prolongation of the axle 29 under the action of a spring 36', and the other beak 37 coacting with a finger 38 provided at the extremity of the lower arm of the cranked lever 24.

30 The putting in gear of the mechanism is shown in Figs. 4 to 6 representing the parts effecting the engagement, the spiral 22 being, according to this embodiment, provided directly on the pinion 20.

35 When the button 34 is in its normal position, the horse head is maintained in its upper position, as shown in Fig. 4, by the finger 23 of the lever 24 raised by the spring 25. The pinion 17 does not mesh with the pinion 20.

40 The finger 38 integral with the finger 23 is equally maintained in raised position and engages the beak 37 of the cam 30.

45 On applying pressure on the button 34 the finger 23 is lowered and the horse head 14 is no more maintained and moves downwardly owing to friction, so that the pinion 17 engages the pinion 20, whereby the putting in gear is effected.

50 At the other part, the finger 38 is equally lowered and moves away from the beak 37 of the cam 30 which therefore is so liberated and since it is solicited by the spring 36', it is taken along by the crank 27.

55 When the cam 30 commences its rotary movement under the action of the crank 27, the finger 38 displaces itself along the outline of the cam which maintains in this way the mechanism in its engaged position.

60 On the cam arriving at the end of the stroke explained later on into its starting position shown in Fig. 4, the finger 38 is apt to engage anew the beak 37 so that the spring 25 is permitted of raising the lever 24 and thereby the horse head 14, whereby an automatic disengagement is effected.

65 On the contrary, when it is desired to vary the opening of the obturator by hand on turning the axle 18 by means of the knurled button 19, the crank 27 effects rotation of the shaft 26 without producing engagement, the cam 30 being impeded to rotate since it engages by the finger 38 the beak 37, and the spring 36' will be alternately stretched, as shown in Fig. 6, and untensioned.

70 The working of the device is as follows:

75 After establishment of the engagement as described above, the eccentric 21 will be set to rotate by the motor of the apparatus through the

medium of the following parts: toothed crown 9, pinion 10, shaft 11 and pinions 16, 17 and 20.

On rotating the eccentric 21 takes along the pin 32 of the rod 31 which displaces itself in the slot 22 in the shape of a spiral of Archimedes of this eccentric. The rod performs consequently a to and fro movement and takes along with itself the crank 27 to which it is articulated at 29.

This crank rotates the shaft 26 and effects in this way the variation of the opening of the obturator, exactly in the same way as it is effected by the control by hand 19, 18, excepting anyhow that this variation controlled by a motor is produced in a continuous and uniform manner.

The crank 27, the rod 31 and its pin and the eccentric 21 are disposed in such manner that the pin occupies the point *a* where the spiral begins to retrace its path when the cam is in its position of disengagement shown in Fig. 4.

Consequently it is obvious that to each rotation 20 of the eccentric 21 corresponds a whole to and fro stroke of the rod and of the crank 27, so that at the end of the stroke of the crank 27 the opening of the obturator returns to the size it occupies 25 in its starting position, after having passed through the opposite value.

It follows therefrom that the mechanism works independently of the initial value of the opening of the obturator. This initial value is controllable by hand with aid of the knurled button 19. 30

In Fig. 7 another embodiment of the engagement device according to the invention is represented. The cam 30 is replaced by a shoe 30' slideable by means of two pins 30'' and 30''' in a second slit 33' of the rod 31. The shoe applies through the medium of its lower left edge against the finger 38 of the cranked lever 24 and is moved toward the left by the spring 36'. When the mechanism is engaged by the lowering of the lever 24 the finger 38 is released, viz., no more kept by the shoe 30' and the latter displaces itself together with the rod 31 under the action of the spring 36'. At the same time the finger 38 travels along the lower border of the shoe, whereby the lever 24 is prevented from moving upwardly. 45

In order to obtain a "found enchain", the start is made either from the complete opening or from the complete closing of the obturator. The pictures are taken up to the moment when the opening of the obturator is closed, if the start 50 has been made in the opened position, or up to the moment of opening if the start has been made in the closed position, at which moment the taking of pictures must be stopped.

Now it is obvious from what has been said, 55 that at this moment the pin 32 of the rod 31 is at the summit *b* of the spiral 22.

In order to inform the operator that this point has been attained, a sonorous device—see Fig. 8—is provided, which comprises a pin 40 fixed to the pinion 20 attached to the eccentric 21, and a hammer 41 fixed to the plate 13 in such manner that when the pin 32 of the rod 31 is at the summit *b* of the spiral 22, the pin 40 raises the hammer 41 which strikes against a sonorous plate or string, 60 65 not shown in the drawings.

On perceiving this signal, the operator arrests the apparatus and proceeds to winding up of a certain number of pictures or views to be taken for the "found enchain". This number is furnished to him by a counter of pictures of any known type. 70

In order to effect this winding up, he must effect rotation of the toothed wheel 10 and of the shaft 11 in a sense opposite to that of un- 75

winding during the taking of pictures. The horse head 14 mounted with friction on the shaft 11 will then be raised and will disengage the mechanism, so that the value of the opening of the obturator will not change during winding up.

On re-starting the taking of views, the horse head 14 gets anew into its lowered position, the mechanism will be engaged and the opening of the obturator will continue up to its size at starting, corresponding to the end of the stroke of the crank 21, at which moment the disengagement will produce itself automatically owing to the finger 38 of the lever 24 being caught by the beak 31, as previously explained.

15 If, on the contrary, it is not desired to make but a simple "found", the taking of views will be arrested on hearing the signal, and the opening of the obturator will be regulated by hand, which opening by hand is rendered possible owing 20 to the friction of the horse head. When re-starting the taking of views the mechanism tending to produce the opening will work without any effect, owing to the friction, the opening having been already made by hand.

25 It is also possible to start the "found" with the closed obturator. For this purpose, the camera being shut, the knurled button attached to the eccentric must be turned after pressing down the button 34 until perception of the audible alarm, whereupon the taking of views is started.

In order to be able to make a more or less long "found" viz. one extending itself over a greater or smaller number of pictures moving in front of 35 the objective during a period of variation of the opening, a speed changing device is provided according to the invention, represented in Figs. 3 and 9.

For this purpose, the pinions 16, 16' and 16'' are 40 loosely fitted on the shaft 11, to which they can be individually fixed by means of the following keying device: a bore is provided in the shaft 11, in its part supporting these pinions and a rod 42 (Fig. 9) projecting outwardly after traversing 45 the plate 13 is provided with a button 43, this rod being lodged in said bore and being shiftable therein. This rod is rotary together with the shaft 11 and carries a spring blade, preferably a cord 44 of steel-wire whose one extremity 50 45 is fixed in a hole 46 provided for this purpose in said rod, whilst the other extremity which is free, is bent to form a boss 47. A longitudinal slit is provided in the shaft 11, through which passes the part of the spring 44 comprising the 55 boss 47 which enters recesses such as 48, provided in the pinions 16, 16' and 16'', whereby the respective pinion into the recess whereof the said boss engages, will be rigidly connected with the shaft 11. The changing of speed can be 60 hence very simply effected by pushing the rod 42 into the bore or by pulling said rod in contrary direction. This movement of the rod is limited by an arresting screw 49 engaging a slit 50 in the shaft 11, and the rod 42 is provided 65 with a recess 51 into which enters the spring 44 and its boss 47 during the passage from one pinion to the other.

The speed of variation of the opening of the obturator is in this way determined by the ratio 70 of each one of the pairs of pinions 16—17, 16'—17' and 16''—17''.

In the above described constructional form of the mechanism three different speeds can be obtained. This number can of course vary according to the requirements, since it is possible to 75

provide as many pinions on the shaft 11 and on the horse head 14 as speeds are required.

Different other modifications can be provided within the scope of the present invention.

The spiral 22, for example, instead of being a 5 spiral of Archimedes, may have any other suitable configuration.

The pin 40, instead of actuating an audible alarm, may effect automatically the standstill of 10 the movement.

It is of course to be understood that the automatic control of the opening according to the invention does not limit itself to its application to a known obturator above described but can be applied to any obturating device securing variable openings.

What I claim, is:

1. An obturating device for cinematographic cameras, comprising two shutters having opening sectors of the same size, the first shutter 20 being fixed on a shaft actuated by the motor of the camera, the second shutter being fixed on a sleeve through which the first named shaft passes, the sleeve being provided with a helicoidal groove, the shaft having a pin entering 25 the said groove of the sleeve, a crank handle adapted to effect a sliding movement of the carrying shaft of the first shutter in the carrying sleeve of the second shutter and for bringing about a variation in the position of the two 30 shutters relatively to each other, a coupling device for inducing the operation of the said crank handle by means of the motor of the camera in a continuous and uniform manner, the said coupling device comprising a pinion meshing with 35 a crown gear actuated by the motor of the camera, the said pinion being fixed to a shaft, a second pinion actuated by said shaft, a lever in slide friction on the said shaft, a third pinion loosely mounted on the said lever and in engagement with the second pinion actuated by the 40 shaft, a fourth pinion adapted to enter into engagement with the third pinion when the lever is lowered towards the same, a cam fixedly connected with the fourth pinion, a rod connected 45 with the cam and carrying a supporting shaft of the crank handle, the end of which is slidable in the supporting shaft of the first obturator for the purpose described.

2. An obturating device for cinematographic 50 cameras, comprising two shutters having opening sectors of the same size, the first shutter being fixed on a shaft actuated by the motor of the camera, the second shutter being fixed on a sleeve through which the first named shaft passes, the sleeve being provided with a helicoidal groove, the shaft having a pin entering the said groove of the sleeve, a crank handle acting on the said shaft for causing it to slide in the sleeve and for causing the pin of said shaft to slide in the helicoidal groove of the sleeve for the purpose of bringing about variation in the respective positions of the opening sectors of the two shutters 55 relatively to each other, a coupling device for rendering operative the said crank handle by the 60 motor mechanism of the camera in a continuous and uniform way, said coupling device including a lever carrying a pinion and adapted to engage another pinion which is fixedly connected with a cam comprising a plate, a groove provided in 65 one of the faces of the plate and having spiral form, said groove being adapted to receive a projection mounted on a bar for guiding said bar, the bar supporting a shaft, said crank handle being keyed to said shaft and the end of said 70 75

crank handle acting on the carrying shaft of the first shutter to bring about its sliding movement and to induce the displacement of the two shutters from each other.

5. An obturating device for cinematographic cameras, comprising two shutters having opening sectors of the same size, the first shutter being fixed on a shaft actuated by the motor of the camera, the second shutter being fixed on a sleeve through which the first named shaft passes, the sleeve being provided with a helicoidal groove, the shaft having a pin entering the said groove of the sleeve, a crank handle acting on the said shaft for causing it to slide in the sleeve and for causing the pin of said shaft to slide in the helicoidal groove of the sleeve for the purpose of bringing about variation in the respective positions of the opening sectors of the two shutters relatively to each other, a coupling device for rendering operative the said crank handle by the motor mechanism of the camera in a continuous and uniform way, said coupling device including a lever pivotally mounted in slide friction on a shaft actuated by the motor of the camera to be raised or lowered and to release or connect the device by means of which the shutters are coupled to each other, an automatic device for maintaining said first named lever in its coupling position and for releasing it automatically, comprising a bell crank lever with two arms, a finger carried by the upper arm of said bell crank lever holding the first named lever and maintaining it in its release position, a finger carried by the lower arm, a cam mounted loosely on the supporting shaft for the crank handle which controls the displacement of the two shutters, said cam having two tips or points, the first tip striking the pivot pin of the rod through which said shaft is actuated, a spring resiliently connecting said cam with said pivot and maintaining the said tip in contact with said pivot, the second tip abutting against the finger of the lower arm when the lever is in its raised position, and said first named lever when disengaged, and the said finger of the lower arm disengaging from the second tip of the cam when said second bell crank lever is lowered by an outer button, the finger then being guided by the contour of the cam, which cam is actuated resiliently from the pivot of the rod with the control shaft so as to prevent the raising movement of the arm and of the first named lever, the last mentioned lever being held in position up to the end of the stroke of the cam and until the finger of the lower arm again comes into engagement with the second tip of the cam.

4. An obturating device for cinematographic cameras, comprising two shutters having opening sectors of the same size, the first shutter being fixed on a shaft actuated by the motor of the camera, the second shutter being fixed on a sleeve through which the first named shaft passes, the sleeve being provided with a helicoidal groove, the shaft having a pin entering the said groove of the sleeve, a crank handle acting on the said shaft for causing it to slide in the sleeve and for causing the pin of said shaft to slide in the helicoidal groove of the sleeve for the purpose of bringing about variation in the respective positions of the opening sectors of the two shutters relatively to each other, a coupling device for rendering operative the said crank handle for the motor mechanism of the camera in a continuous and uniform way, said coupling device including a lever pivotally mounted in slide friction on a shaft actuated by the motor of the camera to be raised or lowered and to release or connect the device by means of which the shutters are coupled to each other, a bell crank lever pivoted on the frame, a spring for pulling the upper arm of said bell crank lever upward, a finger on said arm for holding the free end of the first named lever and for retaining said lever in an elevated position of release, a manual control device for the raising and lowering of the said first named lever, said manual control device comprising an outer button which acts on the upper arm of said bell crank lever so as to depress the said arm and to depress thereby the first named lever which it supports to bring about the coupling of said control device for the shutters to release the same from each other.

5. An obturating device for cinematographic cameras, comprising two shutters having opening

sectors of the same size, the first shutter being fixed on a shaft actuated by the motor of the camera, the second shutter being fixed on a sleeve through which the first named shaft passes, the sleeve being provided with a helicoidal groove, the shaft having a pin entering the said groove, a crank handle acting on the said shaft for causing the pin of said shaft to slide in the helicoidal groove of the sleeve for the purpose of bringing about variation in the respective positions of the opening sectors of the two shutters relatively to each other, a coupling device for rendering operative the said crank handle by the motor mechanism of the camera in a continuous and uniform way, said coupling device including a lever pivotally mounted in slide friction on a shaft actuated by the motor of the camera to be raised or lowered and to release or connect the device by means of which the shutters are coupled to each other, an automatic device for maintaining said first named lever in its coupling position and for releasing it automatically, comprising a bell crank lever with two arms, a finger carried by the upper arm of said bell crank lever holding the first named lever and maintaining it in its release position, a finger carried by the lower arm, a cam mounted loosely on the supporting shaft for the crank handle which controls the displacement of the two shutters, said cam having two tips or points, the first tip striking the pivot pin of the rod through which said shaft is actuated, a spring resiliently connecting said cam with said pivot and maintaining the said tip in contact with said pivot, the second tip abutting against the finger of the lower arm when the lever is in its raised position, and said first named lever when disengaged, and the said finger of the lower arm disengaging from the second tip of the cam when said second bell crank lever is lowered by an outer button, the finger then being guided by the contour of the cam, which cam is actuated resiliently from the pivot of the rod with the control shaft so as to prevent the raising movement of the arm and of the first named lever, the last mentioned lever being held in position up to the end of the stroke of the cam and until the finger of the lower arm again comes into engagement with the second tip of the cam.

6. An obturating device for cinematographic cameras, comprising two shutters having opening sectors of the same size, the first shutter being fixed on a shaft actuated by the motor of the camera, the second shutter being fixed on a sleeve through which the first named shaft passes, the sleeve being provided with a helicoidal groove, the shaft having a pin entering the said groove of the sleeve, a crank handle acting on the said shaft for causing it to slide in the sleeve and for causing the pin of said shaft to slide in the helicoidal groove of the sleeve for the purpose of bringing about variation in the respective positions of the opening sectors of the two obturators relatively to each other, a coupling device for rendering operative the said crank handle by the motor mechanism of the camera in a continuous and uniform way, said coupling device including a lever pivotally mounted in slide friction on a shaft actuated by the motor of the camera to be raised or lowered and to release or connect the device by means of which the shutters are coupled to each other, an automatic device for maintaining the first named lever in its clutch position and for releasing it automatically, said device comprising a bell crank lever with two arms, a finger carried by the upper arm of the said lever

5 maintaining said lever in position and maintaining it in its position of release, a finger carried by the lower arm, a rectangular shoe sliding on the rod which actuates the control shaft for displacing the shutters from each other, a spring fixed at the end of the rod for pulling said rectangular shoe towards said end and for causing it to engage the lower finger during a movement of said rod so as to maintain the arm and the 10 first named lever lowered in coupling position during the entire movement of the arm.

7. An obturating device for cinematographic cameras, comprising two shutters having opening sectors of the same size, the first shutter being 15 fixed on a shaft actuated by the motor of the camera, the second shutter being fixed on a sleeve through which the first named shaft passes, the sleeve being provided with a helicoidal groove, the shaft having a pin entering the said groove 20 of the sleeve, a crank handle acting on the said shaft for causing it to slide in the sleeve and for causing the pin of said shaft to slide in the helicoidal groove of the sleeve for the purpose of bringing about variation in the respective positions of the opening sectors of the two shutters 25 relatively to each other, a coupling device for rendering operative the said crank handle for the motor mechanism of the camera in a continuous and uniform way, said clutching device including 30 a lever oscillating under slide friction upon the shaft controlled by the motor of the camera, a series of pinions mounted loosely on said shaft, said loose pinions being of different diameters and meshing with loose pinions carried by the said lever, these last named pinions on the lever being of a size inversely proportional 35 to the set of first pinions, means for separately locking the first pinions of the said shaft to actuate them together, said pinions being fixed 40 to each other and one of them engaging the pinion on the cam so as to bring about that upon locking together one of the first pinions of the shaft, the eccentric or cam shall be actuated at a speed corresponding to said first named selected pinion, variable speeds also being adapted 45 to be imparted to the cam as desired, and hence progressive displacement of the two shutters from each other being adapted to be exercised over a number of greater or smaller series of 50 cinematographic pictures.

8. An obturating device for cinematographic cameras comprising two shutters having opening sectors of the same size, the first shutter being fixed on a shaft actuated by the motor of the camera, the second shutter being fixed on a sleeve through which the first named shaft passes, the sleeve being provided with a helicoidal groove, the shaft having a pin entering the said groove of the sleeve, a crank handle acting on the said shaft for causing it to slide in the sleeve and for causing the pin of said shaft to slide in the helicoidal groove of the sleeve for the purpose of bringing about variation in the respective positions of the opening sectors of the two shutters 55 relatively to each other, a coupling device for rendering operative the said crank handle for the motor mechanism of the camera in a continuous and uniform way, said coupling device including a lever oscillating under slide friction upon the shaft controlled by the motor of the camera, a series of pinions mounted loosely on said shaft, said loose pinions being of different diameters and meshing with loose pinions carried by said lever, these last named pinions on the lever being 60 of a size inversely proportional to the set of first

pinions, said pinions being fixed to each other and one of them engaging the pinion on the cam so as to bring about that upon locking together one of the first pinions of the shaft, the eccentric or cam shall be actuated at a speed corresponding to said first named selected pinion, variable speeds also being adapted to be imparted to the cam as desired, and hence progressive displacement of the two shutters from each other being adapted to be exercised over a number of greater or smaller series of cinematographic pictures, means for fixedly combining the pinions which are loosely mounted on the control shaft with said shaft, said means comprising a slide rod movable in the interior of the shaft in that part which supports the said pinions, a spring fixed to said rod, a finger at the free end of the spring, a slot in the shaft along one of its generatrix lines to permit the entry of the said projection, sockets in the said pinions at the point of contact with the shaft, a recess in the rod to receive the spring, and its pin when 15 20 25 30 35 40 45 50 55 60 65 70 75

9. An obturating device for cinematographic cameras comprising two shutters having opening sectors of the same size, the first shutter being fixed on a shaft actuated by the motor of the camera, the second shutter being fixed on a sleeve through which the first named shaft passes, the sleeve being provided with a helicoidal groove, the shaft having a pin entering the said groove of the sleeve, a crank handle acting on the said shaft for causing it to slide in the sleeve and for causing the pin of said shaft to slide in the helicoidal groove of the sleeve for the purpose of bringing about variation in the respective positions of the opening sectors of the two shutters relatively to each other, a coupling device for rendering operative the said crank handle for the motor mechanism of the camera in a continuous and uniform way, said coupling device including a lever oscillating under slide friction upon the shaft controlled by the motor of the camera, a series of pinions mounted loosely on said shaft, said loose pinions being of different diameters and meshing with loose pinions carried by the said lever, these last named pinions on the lever being of a size inversely proportional to the set of first pinions, said pinions being fixed to each other and one of them engaging the pinion on the cam so as to bring about that upon locking together one of the first pinions of the shaft, the eccentric or cam shall be actuated at a speed corresponding to said first named selected pinion, variable speeds also being adapted to be imparted to the cam as desired, and hence progressive displacement of the two shutters from each other being adapted to be exercised over a number of greater or smaller series of cinematographic pictures, means for fixedly combining the pinions which are loosely mounted on the control shaft with said shaft, said means comprising a slide rod movable in the interior of the shaft in that part which supports the said pinions, a spring fixed to said rod, a finger at the free end of the spring, a slot in the shaft along one of its generatrix lines to permit the entry of the said projection, sockets in the said pinions at the point of contact with the shaft, a recess in the rod to receive the spring, and its pin when 15 20 25 30 35 40 45 50 55 60 65 70 75

the latter does not enter the socket of one of the pinions, an outer button to cause said rod to slide in the shaft, and also to bring about the entry of the projection of the spring in the socket of one of the pinions corresponding to the speed which the cam is to have, the spring for the pinions of variable speeds being formed by a steel

wire such as a piano wire, one end of which is fixed to the slideable pin in the actuating shaft, and the other end of which is bent back to form a projection which must engage in the sockets provided in said pinions upon sliding of said rod. 5
